UNITED STATES PATENT OFFICE.

JOHN R. HALDEMAN, OF SPRINGFIELD, MISSOURI.

GATE-HINGE.

SPECIFICATION forming part of Letters Patent No. 605,420, dated June 7, 1898.

Application filed September 28, 1897. Serial No. 653,286. (No model.)

To all whom it may concern:

Be it known that I, JOHN R. HALDEMAN, a citizen of the United States, residing in Springfield, county of Greene, and State of Missouri, have invented a new and useful Improvement in Gate-Hinges, of which the following is a specification.

My invention is an improvement in the means for hanging gates intended both to slide and to swing—that is to say, gates which slide on rollers that are journaled on a bar pivoted to a post, so that the gate may turn or swing with it to open or close the roadway.

The chief feature of novelty is the manner of pivoting such gate-supporting pivot-bar, whereby a certain operation results and an important advantage is attained.

In the accompanying drawings, Figure 1 is a side view of a gate supported by my improved hanger. Fig. 2 is a face or front view of my improved hanger. Figs. 3 and 4 are cross-sections on lines 3 3 and 4 4, respectively, of Fig. 2. Fig. 5 is a side view of my improved hanger.

The gate proper is shown constructed in a well-known manner of horizontal bars, end bars 2, and diagonal and vertical braces 3 4. It is supported and slides on flanged rollers 5, which are journaled on the face of a vertical bar 6, pivoted to a post 7, as shown. The details of this construction and combination of parts are as follows:

The gate-supporting and pivot-bar or hanger 6 has a right-angular flange 8, Fig. 5, at each end, the two flanges being parallel and projecting from the inner side of the bar. Each flange 8 is perforated vertically; but, as will be noted in Figs. 2, 3, and 4, the perforations are located diagonally in reference to each other, one being near one side edge of the upper flange 8 and the other near the opposite side edge of the lower flange 6. These perforations are for reception of the pintles of the hooks or hinges 9 9', the upper one point-

ing upward and the other downward to prevent accidental detachment of the bar 6. The upper hook has a screw-threaded shank and the lower one 9' has a smooth shank. To attach the bar 6, the upper hook 9 is screwed into the post 7 and the bar 6 then hung thereon, and the lower hook 9' is next engaged with the bar 6 and then driven into the post 7. The flanged rollers 5 run under the second and between the fourth and fifth bars, respectively, of the gate, as shown.

To operate the gate, its latch 10 is released from the post 11, and then the gate is pushed back on the rollers 5 until it balances thereon, when it may be easily swung open. In such sliding operation, as well as in the reverse or closing movement, the bar 6 is prevented, by reason of the diagonal arrangement of its pivots 9 9', from turning, so as to throw the rollers 5 out of parallelism with the gate-bars 1 and cause their flanges to engage with or bite on the edges of the bars that run on them. In other words, the arrangement of the pivots 9 9' prevents the bar 6 from swinging by mere friction of the gate-bars 1 with the rollers 5 as the gate is slid back and forth.

What I claim is—

1. The combination of the gate proper, having longitudinal guide-bars, with a vertical supporting pivot-bar or hanger, which is provided with parallel horizontal flanges having perforations arranged at diagonally opposite points, as and for the purpose specified.

2. The gate-supporting pivot-bar or hanger arranged vertically in a suitable fixed support, and having parallel, horizontal flanges provided with perforations arranged in diagonal relation, as shown and described for the purpose specified.

JOHN R. HALDEMAN.
